UNITED STATES PATENT OFFICE

LLOYD W. BROWN, OF ROCHESTER, NEW YORK, AND HERMAN T. WOOD, OF CAMP HILL, PENNSYLVANIA

ARCH-SUPPORTING SHOE

Application filed March 10, 1932. Serial No. 598,048.

This invention relates to what may be termed an arch supporting shoe, and the primary object of the invention is to provide a low-cut shoe with an arch support which embodies a flexible non-metallic arch-supporting element, which will effectively support the arch and rock the foot outwardly, and which includes means to adjust the arch supporting element to suit the wearer and secure the shoe on the foot.

Other objects and features of the invention will become apparent from the following description when considered in connection with the accompanying drawings, in which:

15 Figure 1 is a side elevation of an arch supporting shoe embodying the present invention, looking at the inner side of the shoe, and with the shoe proper partly broken away and in section.

20 Figure 2 is a view similar to Figure 1, with the arch support in section.

Figure 3 is a horizontal section on line 3—3 of Figure 1.

Figure 4 is a transverse section on line 25 4—4 of Figure 1.

Figure 5 is a view similar to Figure 4, showing a modification of the invention; and

Figure 6 is a view similar to Figure 4, showing a further modification.

30 Referring in detail to the drawings, the shoe proper is of the low-cut type embodying an outer sole 5, inner sole 6, heel 7, vamp 8, and quarters 9.

In accordance with the present invention, 35 a strap 10 is positioned upon the inside of the shoe so as to extend across the insole under the arch of the foot and then upwardly along the inner side of the foot to a point above the inner quarter 9 where its adjacent 40 end joins with an upward strap extension on the upper edge of said inner quarter to form a loop 11. The other end of the strap 10 is connected to the outer side of the shoe, and an adjustable connection 12 is provided

45 between the inner and outer quarters 9 of the shoe adapted to extend across the instep of the foot to secure the shoe on the foot, the loop 11 being slidable through one end of the connection 12 so that when the latter 50 is shortened the arch supporting element or

strap 10 will be pulled upwardly at the inner side of the shoe to raise and support the arch of the foot and at the same time rock the foot outwardly to its proper normal position.

In Figures 1 to 4 inclusive, the outer end 55 of the strap 10 is secured by stitching 13 to the inner face of the outer quarter 9, preferably beneath the inner lining of the shoe, not shown. In this embodiment, the connection 12 consists of an adjustable instep strap composed of an upward strap extension 14 on the upper edge of the outer quarter 9 having a buckle 15 secured thereon intermediate its ends, and a slotted plate 16 in which the loop 11 is slidably engaged, the free end portion 60 of the strap extension 14 being also slidably inserted through the plate 16 and extended backwardly upon itself for adjustable engagement with the buckle 15.

In Figure 5, the strap extension 14a is 70 shorter and has a buckle 15a attached to the free end thereof, a strap 17 being attached at one end to the plate 16 and adjustably engaged at its other end portion with the buckle 15a.

In Figure 6, the outer end portion of the arch supporting strap 10a extends upwardly along the outer side of the foot and connects with an upward strap extension on the upper edge of the outer counter 9 to form a second 80 loop 11a slidably engaged in a second slotted plate 16a. In this instance, the connection 12 consists of a strap 18 attached at one end to the plate 16 and carrying at the other end a buckle 15b, and a second strap 19 attached 85 at one end to plate 16a and having its other end portion adjustably engaged with buckle 15b. This embodiment is suitable for cases in which the outer side of the arch of the foot requires elevation and support, as well as the 90 inner side of the arch. In use, the outer side of the strap 10a will be adjusted as to elevation by sliding the loop 11a outwardly through plate 16a after which the connection 12 is adjusted while holding the loop 11a 95 against movement through plate 16a, whereby the inner side of the arch is elevated to rock the foot outwardly and properly support the arch.

It will be seen that the present invention 100

provides a simple and inexpensive arch support for low-cut shoes which is efficient in use, and which may be used without discomfort. Minor changes may be made in details of construction without departing from the spirit of the invention as claimed.

What we claim as new is:

1. A low-cut arch-supporting shoe comprising a sole and heel, a vamp, quarters, an arch-supporting strap positioned upon the inside of the shoe so as to extend under the arch of the foot and upwardly along the inner side of the foot to a point above the inner quarter, an upward strap extension on the inner quarter joined to the adjacent upper end of the arch supporting strap to form a loop, the other end of said arch-supporting strap being connected to the outer side of the shoe, and an adjustable connection between the inner and outer quarters adapted to extend across the instep to secure the shoe on the foot, said loop being slidable through one end of said adjustable connection so that the arch-supporting strap will be pulled upwardly at the inner side of the shoe when said connection is shortened to raise and support the arch of the foot and rock the foot outwardly.

2. A low-cut arch-supporting shoe comprising a sole and heel, a vamp, quarters, an arch-supporting strap positioned upon the inside of the shoe so as to extend under the arch of the foot and upwardly along the inner side of the foot to a point above the inner quarter, an upward strap extension on the inner quarter joined to the adjacent upper end of the arch supporting strap to form a loop, the other end of said arch-supporting strap being connected to the outer side of the shoe, an adjustable connection between the inner and outer quarters adapted to extend across the instep to secure the shoe on the foot, said loop being slidable through one end of said adjustable connection so that the arch-supporting strap will be pulled upwardly at the inner side of the shoe when said connection is shortened to raise and support the arch of the foot and rock the foot outwardly, said adjustable connection consisting of an instep strap having one part connected to the top of the outer quarter and another part provided with a slotted member through which said loop slidably passes, and means to adjustably connect said parts of the instep strap.

3. A low-cut arch-supporting shoe comprising a sole and heel, a vamp, quarters, an arch-supporting strap positioned upon the inside of the shoe so as to extend under the arch of the foot and upwardly along the inner side of the foot to a point above the inner quarter, an upward strap extension on the inner quarter joined to the adjacent upper end of the arch-supporting strap to form a loop, the other end of said arch supporting strap being connected to the outer side of the

shoe, and an adjustable connection between the inner and outer quarters adapted to extend across the instep to secure the shoe on the foot, said loop being slidable through one end of said adjustable connection so that the arch-supporting strap will be pulled upwardly at the inner side of the shoe when said connection is shortened to raise and support the arch of the foot and rock the foot outwardly, said other end of the arch-supporting strap extending upwardly along the outer side of the foot and joined to the upper edge of the outer quarter to form a second loop, said second loop being slidable through the other end of said adjustable connection.

In testimony whereof we affix our signatures.

LLOYD W. BROWN.
HERMAN T. WOOD.
